UNITED STATES PATENT OFFICE.

SAMUEL FURMIDGE, OF ST. LOUIS, MISSOURI, ASSIGNOR TO SUPPLEMENTARY SPIRAL SPRING COMPANY, OF ST. LOUIS, MISSOURI, A CORPORATION OF MISSOURI.

VEHICLE-SPRING.

No. 831,276.

Specification of Letters Patent.

Patented Sept. 18, 1906.

Application filed July 13, 1905. Serial No. 269,453.

To all whom it may concern:

Be it known that I, SAMUEL FURMIDGE, a citizen of the United States, residing at the city of St. Louis, State of Missouri, have invented certain new and useful Improvements in Vehicle-Springs, of which the following is a specification.

This invention relates to means for increasing the resiliency in the connections between axles and vehicle-bodies borne thereby.

In the drawings accompanying this specification and forming part of same, and in which like numbers of reference denote like parts wherever they occur, Figure 1 is a side elevation of the rear portion of an automobile-body, showing one form of my invention in side elevation, the near wheel having been removed. Fig. 2 is a similar view illustrating another form of my invention. Fig. 3 is a perspective view illustrating the application of still another form of my invention crosswise to the front of an automobile. Fig. 4 is a side elevation of the front portion of an automobile-body, (the near wheel having been removed,) showing that form of my invention illustrated in Fig. 1 here applied to the front end of a vehicle, the necessary changes having been made. Figs. 5 and 6 illustrate two additional modifications of my invention in side elevation, the near wheel removed. Fig. 7 is an end elevation of the device shown in Fig. 2. Fig. 8 is a detail, on an enlarged scale, in side elevation, of the end portion of the device of Fig. 2. Fig. 9 is a similar detail in section on the line 9-9, Fig. 8. Fig. 10 is a forward end view of the device shown in Fig. 1. Fig. 11 is a top plan view detail of the device as shown in Figs. 5 and 6, and Fig. 12 represents a modification of the helical spring.

The vehicle-body 1 is supported on the axles 2 of the wheels 3, the semi-elliptic springs 4 being attached to the axles by the boxes 5 in the usual manner.

In Fig. 3 the sleeves 6 take the place of boxes 5 on account of the different location and change of construction. In this figure the box 5 attaches the semi-elliptic spring to the vehicle body or frame surmounted by the hood 7.

In all the forms illustrated in the drawings, except that of Fig. 12, a pair of helical springs 8 is used, as clearly appears in Figs. 3, 7, 9, 10, and 11.

Referring now to Fig. 1, it will be evident that one leaf 9 of the semi-elliptic spring 4 is raised at its ends, so as to be there disjoined and separated from the lower leaves thereof. The same arrangement of the leaf 9 will be found in Fig. 4; but in Fig. 5 only one end of the leaf 9 is so raised and disjoined.

In Fig. 3 the arrangement of the leaves of the semi-elliptic spring 4 is inverted with relation to that of Figs. 1, 4, and 5—that is to say, in Fig. 3 the lowest leaf becomes the disjoined member 9, while the spring 4 as a whole arches upward instead of downward, as in Figs. 1, 4, and 5.

In Figs. 1, 3, and 4 a pair of helical springs 8 is shown at each end of the semi-elliptic 4, being located in the space between the end of the disjoined leaf 9 and the next lower leaf 10 in Figs. 1 and 4, (the next upper leaf 10 in Fig. 3.)

In Fig. 5 the pair of helical springs 8 is located between the leaves 9 and 10 at only one end thereof, while the other end of leaf 9 lies flat on leaf 10.

The eyes 11 of leaves 9 and 10 turn in opposite directions and encircle bolts 12, which in Figs. 1 and 4 run through the hanger 13 and bracket 14 mediate to connect the vehicle-body 1 with the axle 2.

In Figs. 5 and 6 the helical springs 8 are substituted for the hanger 13, there being a pair in each instance, the eyes 15 of which encircle the bolts 16, which run through the frame 21, on which in those constructions the vehicle-body 1 rests. The bolt 16 runs clear through the frame 21, and the eye 15 of one helical spring 8 encircles it at the head end, and the eye 15 of the other helical spring 8 of the pair encircles the nut end of bolt 16.

In all the figures (except Figs. 11 and 12) the eyes 11 are either shown or understood to encircle the bolts 12, intervening (as clearly shown in Figs. 3, 7, 9, and 10) between the eyes 17 of the springs 8, which also encircle said bolts 12.

From the foregoing description it will be evident that when weight depresses the vehicle-body 1 the pressure comes first on leaf 9, (in Figs. 1, 3, 4, and 5,) which by itself would be too weak to support the load and would instantly flatten upon leaf 10, depriving the vehicle of nearly all resiliency. When leaf 9 begins to flatten in Figs. 1, 3, 4, and 5, the weight is next thrown upon the helical

2

springs 8, which are supported with considerable firmness by leaf 10 and act as auxiliary springs. Ordinarily the weight is thus absorbed by the helical springs 8. Finally 5 the strain comes upon the leaf 10 and other lower leaves (upper leaves in Fig. 3) of the semi-elliptics 4. The interposition of the helical springs between a pair of semi-elliptic members in such order that the first strain 10 falls upon a semi-elliptic member, following which it is absorbed by the helical springs, and finally by another semi-elliptic member, produces resiliency for the vehicle in a degree that is highly desirable, with an absence 15 of a disagreeable bouncing motion. The close connection between the eyes 11, eyes 17, and bolts 12—that is to say, between the helical springs 8 and the semi-elliptics 4—and of the whole spring structure with the vehicle-body prevents side motion or swaying 20 of the latter, even when turning corners. It will be understood that the arrangement described permits of particularly close binding together of the various parts by reason of the 25 fact that the eye of a semi-elliptic and also the eyes of the helical springs belonging thereto encircle the same bolt. By this arrangement absence of lateral pull or strain on the helical springs and of their bolts is secured, 30 thus decreasing wear and tear and repairs.

In Figs. 2, 7, 8, and 9 a modified structure well within the principle of the foregoing is illustrated with some additional features. A pair of semi-elliptic springs is provided arching in opposite directions, each consisting of 35 several leaves. The upper one is attached to the vehicle-body 1 by a box 5 and the lower one similarly to the axle 2. Passing through the same boxes 5 and bound tightly therein 40 with the semi-elliptics 4 and located between the pair of semi-elliptics is a full elliptic spring 18, the ends of its members being united by bolts and eyes in the usual manner. The lowest leaf 19 of the upper semi-elliptic 45 is provided with upturned eyes 11 and the uppermost leaf 20 of the lower semi-elliptic with downturned eyes 11, bolts 12 passing through each and by means of nuts binding the eyes 17 of a pair of helical springs 8 tightly against 50 the eyes 11. In this structure the weight is first borne by the upper semi-elliptic 4, then it is absorbed by the helical springs 8, and finally by the lower semi-elliptic 4.

In the structure shown in Fig. 6 the weight 55 is received first upon the semi-elliptic spring 4, being conveyed thereto by the bracket 14 and the stiff and comparatively unyielding helical springs 8, and then the weight compresses the pair of helical springs 8, after 60 which any part of the weight which is not resiliently borne by said pair of helical springs 8 is thrown for the sake of additional resiliency upon the leaf-spring 4. In other words, with a light weight the leaf-spring 4 would be 65 adequate to sustain same in a resilient man-

ner. If a greater weight were placed in the vehicle, said leaf-spring might be robbed of its resiliency, and to prevent this occurring the helical springs are provided and such greater weight is borne resiliently by reason 70 of their compression. If, however, a still greater weight be introduced into the vehicle, so that the maximum resiliency of said helical springs does not serve to provide resiliency for the carriage of the greatest weight, 75 just mentioned, a slightly-greater strain will be imposed upon said leaf-spring. If too great, such additional strain will flatten out said leaf-spring and deprive it of resiliency. If only slightly too much, however, for the 80 helical springs to bear resiliently, the leaf-spring will not completely flatten out, and there will therefore remain some resiliency in the combination. It will be understood by those familiar with the use of springs that 85 without the aid of said helical springs a weight too great to be sustained resiliently by the leaf-spring 4 would result in flattening out said leaf-spring in the first instance, and thereby, if no auxiliary means were provided, 90 depriving the vehicle of all resiliency. To prevent this, the comparatively stiff and unyielding helical springs are introduced and come into action when the weight to be borne 95 is too great for the leaf-spring 4 and sufficient 100 to overcome said comparative stiffness and unyieldingness of said helical springs. Then if the weight prove so great that it cannot be borne resiliently with the aid of said helical springs the weight is naturally thrown back 105 again upon the leaf-spring 4, in which some slight resiliency will still reside because ordinarily not completely flattened out, owing to the assistance of said helical springs. If, however, the weight be entirely too great for 110 the whole combination, said leaf-spring would be completely flattened out in the third step of the operation of said parts. Such instances would, however, be rare, and generally the three steps of weight-bearing herein 115 fully described will suffice to provide means for resiliently carrying varying weights. In this figure it will be understood that the eye 11 (not shown) of the semi-elliptic spring 4 turns downward to encircle the bolt 12, 120 which passes through the eyes 17 of the pair of helical springs 8.

In Fig. 12 a modification of the helical springs is shown in which instead of a pair of helical springs 8 a single helical spring 22 is used to connect the leaves 9 and 10 of the structure shown in Figs. 1, 3, 4 and the rear end of Fig. 5 and the leaves 19 and 20 of the structure shown in Figs. 2 and 8. In this structure the eyes 11 encircle the bolts 12, as 125 do also the eyes 23 and 24 on the helical spring 22. It will be noted that the eye 23 is on one side of the semi-elliptics, while the eye 24 is on the other side thereof, both being bolted tightly in place. 130

Having thus described my said invention, what I claim, and desire to secure by Letters Patent, is—

1. In a vehicle-spring, the combination of 5 a pair of leaf members and a pair of helical springs interposed between the ends of same, the ends of said helical members being cross-connected at top and bottom and the ends of said leaf members being connected to said cross-connecting means.
  2. In a vehicle-spring, the combination of 10 a pair of leaf members having eyes turned on their ends, a pair of helical springs having eyes turned on both of their ends, and a pair 15 of bolts running through the eyes of said leaf members and the eyes of said pair of said helical springs.
  3. In a vehicle-spring, the combination of 20 a primary leaf member, a secondary helical member, and a tertiary leaf member, the ends of both said leaf members being turned into eyes, and a pair of helical members interposed between said leaf members at one 25 end thereof and having eyes turned on their ends, and a bolt passing through the eye on one end of said leaf members and the eyes on one end of said helical members, and another bolt passing through the eye of said 30 other leaf member and the eyes at the other end of said helical members so as to unite them all together.
  4. In a vehicle-spring, the combination of 35 a primary leaf member, a secondary helical member compressing a pair of helical springs, and a tertiary leaf member, the ends of both 40 said leaf members being turned into horizontal eyes, and a pair of helical springs interposed between said leaf members at one end thereof and having eyes turned on their 45 ends, and a bolt passing through the eye on one of said leaf members and the eyes at one end of said helical members, and other bolt passing through the eye of said other leaf member and the eyes at the other end of said 50 helical members so as to unite them all together.
  5. In a vehicle-spring, the combination of 55 a plurality of leaf members and a plurality of helical members at each end of said semi-elliptic members, said leaf members being spaced apart at their ends, and a single means cross-connecting said helical springs and attaching same to said leaf-springs whereby weight may be communicated from one to the other.
  6. In a vehicle-spring, the combination of 60 a pair of semi-elliptic members, a full elliptic member interposed between same and having its upper leaf bound in the same box with one of said semi-elliptic members, and its 65 other leaf bound in the same box with the other semi-elliptic member, and a pair of helical springs at each end of said semi-elliptic members and interposed between said ends of both semi-elliptic members and attached thereto.
  7. In a vehicle-spring, the combination of 70 a pair of semi-elliptic members, one arching upward and the other downward, a full elliptic spring interposed between same, said full elliptic spring being bound to the vehicle-body in unison with the semi-elliptic member arching upward and in unison with the semi-elliptic member arching downward to the axle, and a pair of helical springs at each 75 end of the semi-elliptic members and tying same together.
  8. In a vehicle-spring, the combination of 80 a pair of semi-elliptic members, one arching upward and the other downward, a full elliptic spring interposed between same, said full elliptic spring being bound to the vehicle-body in unison with the semi-elliptic member arching upward and in unison with the semi-elliptic member arching downward to 85 the axle, the first-mentioned of said semi-elliptic springs having eyes turned on both ends arching upward, and the latter of said semi-elliptic springs having like eyes turning downward, bolts running through said eyes, 90 and a pair of helical springs at each end of said semi-elliptic springs and interposed between same and firmly united thereto by the said bolts.
  9. In a vehicle-spring, the combination of 95 a pair of semi-elliptic members, a full elliptic member interposed between same and having its upper leaf bound in the same box with one of said semi-elliptic members, and its other leaf bound in the same box with the 100 other semi-elliptic member, and a pair of helical springs at each end of said semi-elliptic members and interposed between said ends of both semi-elliptic members and attached thereto, said full elliptic member being out 105 of contact with the members joining together the ends of said semi-elliptic members.
  10. In a vehicle-spring, the combination of 110 a primary leaf member, a secondary helical member, and a tertiary leaf member, the ends of both said leaf members being turned into eyes, said helical member being interposed between said leaf members and having eyes on the ends thereof, the eye on one of said leaf members and the eye on one end of the helical member being arranged in horizontal alinement, and the eye on the other leaf member and the eye on the other end of the helical member also horizontally alining, and bolts passing through said eyes to 115 bind the leaf and helical members together.
- In testimony whereof I have affixed my signature in presence of two witnesses.

SAMUEL FURMIDGE.

GLADYS WALTON.

Correction in Letters Patent No. 831,276.

It is hereby certified that in Letters Patent No. 831,276, granted September 11, 1906, upon the application of Samuel Furmidge, of St. Louis, Missouri, for an improvement in "Vehicle-Springs," an error occurs in the printed specification requiring correction, as follows: In line 34, page 3, the word "compressing" should read *comprising*; and that the said Letters Patent should be read with this correction therein that the same may conform to the record of the case in the Patent Office.

Signed and sealed this 15th day of January, A. D., 1907.

[SEAL.]

F. I. ALLEN,
Commissioner of Patents.
